UNITED STATES PATENT OFFICE.

RALPH D. MERSHON, OF NEW YORK, N. Y.

ELECTROLYTIC RECTIFIER.

1,171,969.

Specification of Letters Patent. Patented Feb. 15, 1916.

Application filed January 23, 1912. Serial No. 672,896.

To all whom it may concern:

Be it known that I, RALPH D. MERSHON, a citizen of the United States, residing at New York, in the county and State of New York, have invented certain new and useful Improvements in Electrolytic Rectifiers, of which the following is a full, clear, and exact description.

It is well known that while the efficiency 10 of the electrolytic rectifier in its present commercial form may, under some conditions, be fairly high, it diminishes very materially if the device is operated continuously for any considerable length of time. 15 This drop or diminution is apparently attributable to two principal causes—the increase in the temperature of the rectifier and its electrolyte, and the accumulation of bubbles of gas on the electrodes, particularly on 20 the filming electrode. The first of these contributing causes,—that of increased temperature—may be, to a large extent, overcome by the provision of a radiating surface of sufficient extent, and in practice this course is 25 generally followed. But as the efficacy of any given radiating surface, depends largely upon the completeness and rapidity of circulation of the electrolyte in the containing vessels, the usual means for promoting circulation, by such design of the vessel that 30 it will be effected by convection due to the heat generated in the electrolyte, have not proved adequate, heretofore, to obviate this objection and secure the desired result. Of 35 course, the circulation could obviously be increased to any desired degree by the employment of some form of pump or other externally operated power device, but any such auxiliary apparatus is manifestly objectionable, being more or less cumbersome, expensive and uneconomical.

The invention which forms the subject of my present application affords, incidentally to its main purpose, a simple and effective 45 means for promoting a thorough and rapid circulation of the electrolyte, without resorting to the use of any auxiliary devices or the application of external sources of power for the sole purpose of securing circulation.

I have found from investigations of the matter what has not been generally recognized, that the bubbles adhering to the filming electrodes are largely responsible for the

decrease in the efficiency of the rectifiers attendant upon continued use. In the case of those commercial forms of this apparatus, which evidence an apparent recognition, on the part of the manufacturers, of this source of trouble, the precautions for the removal or elimination of these bubbles have been limited to efforts to direct the convection currents in the electrolyte so as to sweep the bubbles off from the filming electrodes. This plan, while partly effective, falls far short of remedying the difficulty, as a great many minute bubbles adhere so firmly to the electrodes as to resist dislodgment by such convection currents as it is feasible to obtain. This may be demonstrated by plunging a piece of metal, especially if its surface be slightly rough, into a glass of clear water. The bubbles which form on and adhere to the surface of the metal will not be displaced by even a comparatively violent stirring movement of the metal in the water, but if the metal be raised out of the water, even though it be immediately returned, it will be found that a large part if not all of the bubbles have disappeared. With the object of utilizing this action in electrolytic valves and rectifiers, in which I have found that it occurs in the case of filming electrodes, I have devised the plan of displacing the electrolyte from the containing vessel so as to expose momentarily the electrode or electrodes and then permit its return. To accomplish this I place the filming electrode in a closed chamber, expel the electrolyte from such chamber by the action of air or gas under pressure and then liberate the body of confined air or gas to permit the return of the electrolyte. The compressed air or gas may be obtained from any source, but as an external source is not always available I propose to utilize the gas generated by electrolytic action to effect a periodic displacement of the electrolyte and consequent exposure of the electrode or electrodes, and incidentally to promote such circulation of the electrolyte as greatly assists in dislodging the bubbles as they form.

The specific embodiment of the invention or improvement is illustrated in the accompanying drawings in which—

Figures 1, 2, 3, 4 and 5 are sectional views of single "electric valves" illustrating the principle and various details and modifica-

tions of the improvement, and Figs. 6 and 7 similar views of electrolytic rectifiers illustrating the application of the improvement to apparatus of that particular class.

5 The electric valves above referred to, consist of an aluminum filming electrode A located inside an air tight inverted bell jar B of metal forming the non-filming electrode, although, of course, the bell may be 10 of non-conducting material and a non-filming electrode, either without or within the bell employed, preferably the latter, as some bubbles are set free from the non-filming electrode which assist those from the filming electrode in effecting the operations described below. A tube C of small diameter and having one end bent back upon itself extends through an air-tight connection in the top of the bell B, and the parts named 15 are suitably supported in a containing vessel D partly filled with an electrolyte. The conductor E leading from electrode A is insulated from the bell B and the electrolyte and the tube C may be of metal in which 20 case it may serve as a terminal for the non-filming electrode.

The action of the device may be best explained by a description of one cycle of operation.

30 Assuming that the containing vessel is filled to the normal level with electrolyte and the filming electrode properly formed, the bell and the small bent tube C will be filled with the electrolyte up to the level of 35 the main body in the vessel D. If now the terminals of a source of alternating current be attached, one directly to one electrode and the other to the opposite electrode through the load to which the "electric valve" is to 40 supply unidirectional current, bubbles of gas will be formed at the surface of both, but mainly at that of the filming electrode. The greater part of these gas bubbles will be disengaged by their own buoyancy and 45 rise to the top of the bell displacing the electrolyte, but many will remain clinging to the electrodes. This displacement of the electrolyte will expose more and more of the surface of the filming electrode permitting 50 it to free itself of the adhering bubbles, and this action will continue until, by the pressure of the gas, the electrolyte in the tube C is expelled and the gas confined in the bell B is allowed to escape. It will be under- 55 stood that as the level of the liquid is forced down in the bell, it is also forced down the short leg of the bent tube C, and up the long leg of the same. As soon as the liquid has thus been forced around the bend of 60 the tube the head of liquid in the long leg no longer increases as the liquid moves, and therefore any increase of pressure in the bell, will drive all the liquid in the tube C out into the open vessel, thus permitting the 65 gas in the bell to escape and the electrolyte

to again rise in the bell to the level of the end of the short leg of the tube, at which point the electrolyte enters the tube and prevents a further escape of gas. This action will be repeated with cyclic regularity.

70 It is evident that the distance to which the electrolyte will be forced down in the bell B will depend upon the length of the short leg of the U-tube C, or upon the total length of the column of electrolyte in the 75 long leg of said tube when all of the electrolyte has passed around the bend in the tube or in general upon the particular configuration of the tube which determines the point at which an increased head or height of 80 column of liquid in the tube is no longer produced by a movement of the liquid in the electrode chamber or tube. The device should, therefore, be so arranged that the tube C will discharge before the filming 85 electrode has been entirely exposed, so that there will be still a portion of the electrode immersed to form bubbles and therefore increase the pressure in the bell.

In order to obtain a uniform rate, or, if 90 desired, a varying rate of movement of the surface of the electrolyte with respect to the electrode, the shape of the bell B may be modified, as for example as shown in Fig. 2, whereby contracting the lower portions of 95 the bell the rate of movement will be more nearly uniform, since the volume of gas generated is greatest when the electrode is fully immersed in the electrolyte.

100 In an apparatus organized and constructed as above described, it is evident that the bubbles will be cleared off periodically from the greater part of the filming electrode, by the withdrawal of the electrolyte therefrom. The bubbles from its lower end which is not 10 exposed will be cleared off by the violent inrush of electrolyte which follows the discharge of the tube C. It is also apparent that this periodic movement of the electrolyte will produce in the same a much more 11 complete and rapid circulation than could be produced by convection currents alone.

110 From the nature of the apparatus and its operation thus described, it will be seen that the current passing through the "valve" 11 will be periodically diminished because of the reduction of the active area of filming electrode in contact with the electrolyte. To overcome this objection the plan may be resorted to which is illustrated in Fig. 3, in 12 which there are two electrodes A and A', the latter of which is covered by the electrolyte at the same rate that the first is exposed, so that the aggregate area of filming electrode in contact with the electrolyte is constant. 12 In order that this relation may be maintained the surface of the electrolyte outside the bell B must be caused to rise at the same rate that the level sinks in the bell, for 13 which purpose the upper portion of the con-

taining vessel is constricted as shown in Fig. 3. A similar result will be secured by making the upper filming electrode shorter and thicker than the other as shown in Fig. 4. In this latter figure is shown also an additional feature providing for a more definite and constantly directed circulation of the electrolyte. In this case the bottom of the bell B is closed, and provided with two mechanical valves F and G, opening in opposite directions. There is also arranged across the containing vessel D a septum H which divides the space outside the bell and up to the top of the latter into two compartments each containing one of the valves above mentioned. It results from this that the electrolyte is always forced out of the bell on one side of the septum and forced into it on the other side. A similarly definite and directed circulation may be secured by the modification shown in Fig. 5, which obviates the use of mechanical valves. In this device the bottom of the bell B opens into one of the two longitudinal compartments of the vessel D, formed by a septum H, while the lower end of the bell has a number of openings K made small or tortuous so as to resist a rapid flow of liquid. By the generation of gas under the bell the hot electrolyte is slowly forced downward and flows out through the openings K into one of the compartments formed by the septum, but when by the escape of gas through the tube C, there is a rapid inrush of liquid to refill the bell, it enters from the other compartment through the open bottom of the bell. Thus the warm electrolyte constantly rises on one side of the septum, and the cool descends on the other.

In the figures above described the illustrations have been confined to single "valves" which rectify only half of each alternating current wave, but the improvements are also applicable to complete rectifiers for rectifying both halves of the wave, and such embodiments of the invention are shown in the remaining figures, Fig. 6 being designed more particularly to illustrate the principle. In this figure there are two containing vessels L and M, the former and upper being open, the latter closed air tight. The two vessels are connected by a pipe N through which the liquid is transferred from one to the other and which is formed or connected with a cooling coil O, intermediate to the two vessels. A U-tube C similar to that heretofore described connects the two vessels, and in other respects the arrangement is the same as that previously set forth, except that two filming electrodes A, A, are used in each vessel, and a non-filming electrode P of iron or lead. The electrical connections usual for such devices are shown in this figure, but being well understood are not described in detail.

It is evident from the foregoing description of operation that the electrolyte will be forced from the lower into the upper vessel thus periodically uncovering the electrodes in the former, and then returned from the upper to the lower vessel as soon as the gas escapes from the latter through the tube C.

In Fig. 7 is shown a construction by which the explosive circulation is caused to maintain the same direction of movement as that incident to that due to convection. The non-filming electrodes P in this case are in the form of cylinders with numerous perforations through which convective circulation can take place at any height of liquid. A pipe R with a single opening concentric with the cylindrical electrode in the upper vessel extends from the bottom of said vessel into the lower part of the lower vessel where it is provided with two or more orifices surrounding the cylindrical electrode P therein. Similarly, a pipe S with openings surrounding the cylinder P in the upper vessel leads by a single orifice to the center of the lower vessel. The pipes R and S contain ball check valves T and V, the former permitting an upward and the latter a downward flow of liquid only. In other respects than those noted the construction of the device is or may be the same as that illustrated in Fig. 6, and its operation will be understood without further explanation.

It is apparent from such modifications of the invention as I hereinbefore described, that many others are permissible, and that the improvement is not limited to the specific device shown.

What I claim is:—

1. The method of depolarizing the electrodes of electrolytic rectifiers and similar apparatus by the removal of bubbles therefrom, which consists in displacing an electrolyte from the vessel containing the electrodes by the accumulation therein of a gas under pressure and periodically liberating and discharging the accumulated gas to permit the return of the electrolyte, as set forth.

2. The method of depolarizing the electrodes of electrolytic rectifiers and similar apparatus by the removal of bubbles therefrom, which consists in displacing an electrolyte from the vessel containing the electrodes by the accumulation therein of a gas under pressure, and effecting by the pressure of a given volume of such gas the periodic liberation and discharge of the same, to permit the return of the electrolyte, as set forth.

3. The herein described method of depolarizing the electrodes of electrolytic rectifiers and similar apparatus by the removal of bubbles therefrom, which consists in alternately exposing the electrodes to a gaseous medium and bringing about resubmergence of the electrodes in an electrolyte.

4. The combination with a closed chamber, an electrolyte in said chamber, and an electrode immersed in the electrolyte in said chamber; of a vessel into which the electrolyte displaced by the accumulation of gas in the electrode chamber flows, and means for permitting the escape of the confined gas intermittently, and thereby permitting the return to the electrode chamber of the displaced electrolyte, as set forth.

5. An electrolytic apparatus comprising in combination an open chamber, a closed chamber connected therewith, electrodes contained in both of said chambers, an electrolyte, and a gas discharge valve operated by the pressure of a given volume of gas confined in the closed chamber, whereby electrolyte displaced from the closed to the open chamber by the accumulation of such gas will be intermittently returned to the closed chamber, as set forth.

6. An electrolytic apparatus comprising in combination, an open chamber, a closed chamber communicating therewith, electrodes contained in both of said chambers, an electrolyte, and means for compensating for the displacement of electrolyte from one chamber to the other so that the area of active electrode surface is preserved constant, as set forth.

7. In an electrolytic apparatus the combination of an electrolyte, an open electrode chamber and a closed electrode chamber communicating therewith and shaped or formed so that the generation of gas therein by electrolytic action displacing the electrolyte and forcing it into the open chamber will lower the level of such electrolyte at a uniform rate, as set forth.

8. In an electrolytic apparatus, the combination of an open chamber, a closed chamber, electrodes in both of said chambers, an electrolyte, passages of communication between said chambers whereby the development of gas in the closed chamber will expel electrolyte therefrom into the open chamber and the escape of the confined gas will permit the return of the electrolyte, and means for causing the circulation produced by expulsion of electrolyte from the closed chamber to maintain the direction of movement incident to the circulation pro-

duced by convection in the electrolyte, as set forth.

9. The combination of a vessel, a closed electrode chamber communicating at its lower end with said vessel, an electrolyte in the closed chamber, electrodes immersed in the electrolyte in the closed chamber, and a U-tube extending from the closed chamber into said vessel and constituting an automatic valve for the periodic escape of the gas generated in the closed chamber, as set forth.

10. The combination with an open containing vessel, of a closed vessel, an electrolyte, connecting pipes or tubes between the lower portion of said vessels whereby electrolyte displaced from the closed vessel will flow into the open vessel and return by gravity when the displacing pressure is relieved, electrodes immersed in the electrolyte contained in said vessels and a U-tube one leg of which extends from the closed into the open vessel to constitute an automatic valve for the periodic escape of gas generated in the closed vessel, as set forth.

11. The combination of a containing vessel, an electrolyte therein, an electrode normally immersed in the electrolyte, and means for intermittently causing exposure of the normally submerged surface of the electrode to a gaseous medium.

12. The combination of an electrolyte, electrodes normally immersed in the electrolyte, and means for intermittently and alternately exposing the normally submerged surfaces of the electrodes to a gaseous medium.

13. The combination of an electrolyte, electrodes adapted for submergence therein, and means for intermittently causing progressive exposure of one electrode to a gaseous medium and progressive submergence of the other, whereby the total submerged electrode-surface is maintained substantially constant.

In testimony whereof I affix my signature in the presence of two subscribing witnesses.

RALPH D. MERSHON.
